UNITED STATES PATENT OFFICE.

SIDNEY BLUMENTHAL, OF NEW YORK, N. Y.

DESIGN FOR A PILE FABRIC.

No. 39,163.

Specification for Design.

Patented Feb. 25, 1908.

Application filed January 15, 1908. Serial No. 411,025. Term of patent 3½ years.

To all whom it may concern:

Be it known that I, SIDNEY BLUMENTHAL, a citizen of the United States, and resident of the borough of Manhattan, in the city and State of New York, have invented a new, original, and ornamental Design for a Pile Fabric, of which the following is a specification, reference being had to the accompanying drawing, forming part thereof.

My new, original and ornamental design for a pile fabric is shown in perspective in the accompanying drawing.

I claim:—

The ornamental design for a pile fabric, as shown.

SIDNEY BLUMENTHAL.
